UNITED STATES PATENT OFFICE

165,869

KITCHEN TONGS

Donald A. Reiner, Minneapolis, Minn., assignor
to Brown & Bigelow, St. Paul, Minn.

Application September 1, 1950, Serial No. 12,026

Term of patent 14 years

(Cl. D44—4)

To all whom it may concern:

Be it known that I, Donald A. Reiner, a citizen of the United States, residing in Minneapolis, county of Hennepin, and State of Minnesota, have invented a new, original, and ornamental Design for Kitchen Tongs, for which the following is a specification, reference being had to the accompanying drawings, forming part thereof.

Figure 1 is a longitudinal side view of kitchen tongs in open unlocked position, showing my new design.

Figure 2 is a longitudinal side view of kitchen tongs showing them in closed locked position.

Figure 3 is a plan view of tongs as illustrated in Figure 2.

Figure 4 is an end view of tongs as illustrated in Figures 2 and 3.

The characteristic features of my design reside in the portions shown in the drawing by means of full lines.

I claim:

The ornamental design for kitchen tongs, as shown and described.

DONALD A. REINER.
